VENTILATED TOILET

Andrew P. Riedele, Los Angeles, Calif.

Original application December 2, 1941, Serial No. 421,302. Divided and this application November 13, 1945, Serial No. 628,243.

5 Claims. (Cl. 4—217)

1

This application is a division of my application for Letters Patent of the United States of America relating to a ventilated toilet, Serial No. 421,302, filed December 2, 1941, matured as Patent Number 2,389,165, dated November 20, 1945, and wherein is disclosed and claimed a means, which, in association with a toilet, functions to remove from the toilet bowl, all odors resulting from the use of the toilet or originating in the bowl or trap thereof, and to conduct such odors from the premises so as to prevent contamination of the air in the premises.

An object of the present invention is to provide a ventilated toilet and a ventilating unit or adapter structurally characterized to permit its application to a toilet of the type having a rear extension or tail piece on its seat, and cover, if used, which co-acts with brackets and a pivot pin to mount the seat and cover on the adapter, all in such manner that the seat and bowl structure require no alteration; a proper sealing fit is assured between the adapter and sealing members located on the seat and adapter, so as to prevent leakage of odorized air from the bowl into the premises; and an air inlet of maximum efficiency to fully utilize thermal action in conducting bowl odors therefrom into the adapter, assured.

It is another object of the present invention to provide a ventilating unit or adapter of the above described character which is simple in construction, inexpensive to manufacture, compact and neat in appearance, and capable of being installed on a toilet with ease and dispatch.

With these and other objects in view, the invention resides in the combination, arrangement and functional relationship of elements as set forth in the following specification and particularly pointed out in the appended claims.

In the accompanying drawing,

Figure 1 is a plan view of a toilet showing the present invention applied thereto;

Figure 2 is a view of the toilet in side elevation with the invention applied thereto;

Figure 3 is a fragmentary vertical sectional view taken on the line 3—3 of Figure 1; and

Figure 4 is a bottom plan sectional view taken on the line 4—4 of Figure 2.

Referring specifically to the drawing, a ventilating unit or adapter designated generally at V', is shown applied to the toilet bowl B' of a toilet of well known construction whose seat S' has a relatively narrow tail piece 60 to which is secured by screws 61, upstanding bearing arms 62 between which projects a tail piece 63 on the cover C' having a pivot pin 12a extending

2

through the bearing arms 62 and into brackets 65 projecting from the ventilating adapter, with at least one of the brackets being removable for assembling purposes and being secured to the adapter by a screw 66 as shown in Figures 1 and 2.

The ventilating adapter V' comprises a body having a tubular portion or pipe section 20a open at its ends to provide one or more outlets as desired and indicated at 21a. The portion 20a is provided with a lateral or peripheral opening 22a in the form of a slot defining an inlet from a laterally projecting housing portion 24a formed by a top wall 25a and side walls 26a leaving the forward end and bottom open.

Adjacent opposite ends of the tubular portion 20a, threaded attaching studs 14a depend from the adapter and are adapted to be inserted through vertical openings in the flat rearward extension 45a projecting from the back of the bowl. The studs 14a are provided with nuts 16a to rigidly secure the adapter to the bowl with the bottom edge of the housing portion 24a clamped tightly against the top surface of the extension 45a, whereby to close the open bottom of the housing portion 24a to define a duct 36a having an inlet 37a at the rear portion of the bowl as clearly shown in Figure 3.

The top wall 25a is cut away to receive the tail piece 60 of the seat S', which projects into the tubular portion 20a in the lowered position of the seat. The cut-away portion of the top wall 25a is shaped to provide a sufficiently close fit against the confronting portion of the seat S' when lowered onto the bowl as shown in Figure 2, to form a satisfactory seal.

Secured to the underside of the seat S' by headed fastening members 50a, are gaskets or sealing members 51a of a contour to rest upon the rim 18a of the bowl in the lowered position of the latter, so as to seal the space between the seat and the bowl with the exception of a portion at the rear of the bowl corresponding to the width of the duct 36a at its inlet 37a, and a portion at the front of the bowl to provide a fresh air inlet 54a, it being noted that the forward edges of the sidewalls 26a press tightly against the rear ends of the gaskets 51a for sealing contact therewith as shown in Figure 4.

Secured by screws 31a and a metal bar 32a to the tubular portion 20a adjacent the top of the opening 22a, is the attaching flange 33a of a tubular sealing member 34a constructed of resilient rubber or other suitable material. The member 34a spans the width of the opening 22a

and is disposed to be engaged and compressed by the seat S' in its lowered position as shown in Figure 3, so as to effectively seal any space between the top of the opening and the seat.

With the adapter V' installed on the bowl B', a vent pipe 41a is secured in one end of the tubular portion 20a by a set screw 43a, and a cup-shaped closure 44a is secured in the other end of the portion 20a by a set screw 45a. The vent pipe 41a is extended through the wall of the room, preferably to the outer atmosphere.

Any and all odors existing in the bowl when the toilet is in use, will be drawn into adapter V' by natural thermal action, it being noted that the air inlet 54a between the forward spaced ends of the gaskets 51a insures a supply of fresh or unodorized air into the bowl and across the latter from front to rear to most effectively utilize the thermal circulation in removing all bowl odors from the premises.

By the provision of the construction and functional relationship of elements of the adapter V' as above described, the invention can be applied and installed in the very restricted space remaining between the rear end of the tail piece 60 of the seat S' and the front of the flush tank as will be apparent from Figures 1 and 2, all without requiring any modification of this standard type of toilet.

I claim:

1. In a ventilated toilet, a bowl; a seat therefor having a tail portion; a ventilating adapter having a tubular portion with a peripheral inlet and with an outlet adapted for connection to a vent pipe; means for securing the adapter to the bowl; and means pivotally mounting the seat on the adapter, with said inlet disposed between the bowl and the undersurface of said seat and with the tail portion of the seat projecting through said inlet into said tubular portion when the seat occupies its lowered position on the bowl.

2. In a ventilated toilet, a bowl; a seat therefor having a tail portion; a ventilating adapter having a tubular portion provided with a peripheral inlet and with an outlet adapted for connection to a vent pipe; means for securing the adapter to the bowl; brackets projecting from said tubular portion; a pivot pin mounted in said brackets; and bearing arms projecting from the seat and receiving the pin to pivotally mount the seat thereon with said inlet disposed between the bowl and undersurface of the seat, and with the tail portion of the seat projecting into said tubular portion through said inlet, when the seat occupies its lowered position on the bowl.

3. In a ventilated toilet, a bowl; a seat therefor having a tail portion; a ventilating adapter having a tubular portion provided with a peripheral inlet and with an outlet adapted for connection to a vent pipe; means for securing the adapter to the bowl; brackets projecting from said tubular portion; a pivot pin mounted in said brackets; bearing arms projecting from the seat and receiving said pin to pivotally mount the seat thereon with said inlet disposed between the bowl and undersurface of the seat, and with the tail portion of the seat projecting into said tubular portion through said inlet, when the seat occupies its lowered position on the bowl; and a yieldable sealing member secured to the tubular portion to span the top of said inlet for sealing engagement by the tail portion of the seat when occupying its lowered position.

4. In a ventilated toilet, a ventilating adapter comprising: a tubular portion having a lateral inlet and an outlet; attaching studs depending from the adapter for connection to the toilet bowl; brackets projecting from said tubular portion and adapted for co-action with a pivot pin to mount a toilet seat on the adapter; and a sealing member spanning the top portion of said inlet for sealing engagement by the tail portion of the toilet seat when the tail portion projects into said tubular portion.

5. In a ventilated toilet of the type whose seat is provided with a rearwardly projecting tail portion, comprising: a tubular portion having a lateral inlet adapted to receive the tail portion of the seat, and provided with an outlet; attaching studs depending from the adapter for connection to the toilet bowl; and brackets on the adapter, adapted for co-action with a pivot pin, to mount the tail portion of the seat on the adapter for rising and lowering movements with respect to the bowl of the toilet.
